Patented Jan. 30, 1917.

UNITED STATES PATENT OFFICE.

WARREN B. MOULTON AND EDWIN W. MOULTON, OF RIVERSIDE, CALIFORNIA.

VEHICLE DIRECTION-INDICATOR.

1,214,058.

Specification of Letters Patent. Patented Jan. 30, 1917.

Application filed January 11, 1916. Serial No. 71,398.

To all whom it may concern:

Be it known that we, WARREN B. MOULTON and EDWIN W. MOULTON, both citizens of the United States, residing at Riverside, 5 in the county of Riverside and State of California, have invented a new and useful Vehicle Direction-Indicator, of which the following is a specification.

This invention relates to a vehicle direction indicator which is designed to be carried upon a vehicle, will indicate to approaching vehicles the contemplated movement of the vehicle to which it is attached and may be operated from the driver's seat.

15 The primary object of this invention is to simplify the construction and operation of vehicle direction indicators of the character described so as to render them reliable and efficient in operation, capable of being constructed comparatively small and inexpensive to manufacture.

Another object is to provide simple, reliable and compact electrical means for operating an indicating member forming a part 25 of the device.

Other objects and advantages may appear in the subjoined detail description.

The accompanying drawings illustrate the invention.

30 Figure 1 is a front elevation of the device showing the arrow in its various signalling positions in dotted lines and in normal position in full lines; Fig. 2 is a vertical sectional view; Fig. 3 is a vertical sectional view taken on line 3-3 of Fig. 2; Fig. 4 is 35 a diagrammatic view showing the electrical circuit; and Fig. 5 is a fragmentary elevation showing the returning spring.

Referring to the drawings, 1 designates a 40 casing or housing of any suitable construction which may be secured to or formed as a part of the vehicle to which the device is to be attached. Journalized centrally in the front wall 2 of the housing 1 is a horizontal 45 shaft 3, upon the outer end of which is fixed an indicating member 4, which, in this instance, is in the form of an arrow. This arrow is normally held in vertical position by operating mechanism, which is designated 5 5 as an entirety and is mounted within the casing 1. The outer face of the front wall 2 of the casing may be painted or otherwise suitably colored to permit the arrow to be plainly seen, it being preferable to have the 55 arrow painted or colored a bright hue.

The operating mechanism 5 comprises solenoids 6 and 7 which are fixed to the wall 2 of the casing 1, are of arcuate formation and arranged arcuately above the shaft 3 which extends into the casing 1 centrally 60 thereof. Fixed upon and depending from the shaft 3 is an arcuate armature 8, which, in this instance, is U-shaped or, more correctly speaking, semi-circular. Extending upwardly from a point centrally of the ends 65 of the armature is an arm 9 which is rigidly but detachably secured to the shaft 3. The armature 8 is substantially concentric with the solenoids 6 and 7 and is so mounted relative to the shaft 3 that the arrow 4 is normally held in vertical position.

Preferably there is provided means for holding the shaft, armature and arrow against negative movement. This means comprises a spring arm 10 which is secured 75 to and projects at right-angles from a post 11 carried by the front wall 2 of the casing. Carried upon the arm 9 near the free end thereof is a spring-engaging member 12 having a flat face 13 for engagement with the 80 spring arm 10. The arm 10 pressing against the flat face 13 holds the armature 8 and consequently the shaft 3 and arrow 4 against negative movement.

The electric circuit for the operating 85 mechanism 4 comprises a battery or other source of current 14 and circuit-closing means 15 which, in this instance, is in the form of a two-point switch. This switch 15 may be mounted upon the steering wheel 90 of the vehicle, not shown, or at any other point accessible to the driver. From one side of the battery or source of current 14 a conductor 16 leads and is connected with the switch 15. From the other side of the 95 battery or other source of current 14, a conductor 17 leads and is connected by conductors 18 and 19 with the respective solenoids 7 and 6. A conductor 20 connects the solenoid 6 with the switch point 21 of the two-point switch and a conductor 22 connects the solenoid 7 with the point 23 of the two-point switch. An insulation strip 24 carrying binding posts 25 is mounted within the casing 1 and the wires 17, 20 and 22 are 100 connected with said posts 25, the latter being connected with the solenoids as above described.

Normally the arrow 4 is in vertical position and the armature 8 is in the position 110

shown in Fig. 4 of the drawings. When a right-turn is to be made, the driver operates the switch 15 as shown in Fig. 4, so that it contacts with the point 23, and closes the circuit for the solenoid 7, said circuit being traced as follows: from battery 14 through wire 16, switch 15, wire 22, solenoid 7 and through wires 18 and 17 back to battery 14. It will be seen that upon the energization of the solenoid 7 the armature 8 will be drawn into the solenoid 7 and this causes the shaft 3 to rotate and the arrow to be moved from normal vertical into horizontal position and to point toward the right. After the signaling has taken place the operator opens the switch 15, and the armature 8, by force of gravity will immediately assume normal position, causing the arrow 4 to assume its normal vertical position. A similar operation is had when the solenoid 6 is energized, and in this connection the circuit therefor may be traced as follows: from battery 14 through conductor 16, switch 15, conductor 20 through solenoid 6 and from solenoid 6 back to battery 14 through conductors 19 and 17.

The solenoids 6 and 7 have hollow cores and the arcuate armature extends into the cores when the solenoids are energized, a distance equal to half its length. The arm 9 abuts the free ends of the solenoids and since the arm is located centrally of the ends of the armature, it limits the armature movement to 90°. In order to provide for the full 90° movement of the shaft and armature the solenoids at the free ends thereof are each recessed as at 26 upon their opposed sides. These recesses 26 allow the arm 9 to move a full 90°.

It is understood that the invention is not limited to the exact construction shown in the drawings and described above, but that deviations therefrom may be made within the spirit and scope of the invention.

We claim:

1. A vehicle direction indicator comprising a casing, a shaft journaled in said casing and extending out therefrom, an indicating member secured to and extending at right-angles from the shaft upon the outer end thereof, electromagnets mounted within the casing above and on opposite sides of the shaft, an armature fixed to said shaft, an electrical circuit for said magnets, a spring arm mounted within said casing and a spring-engaging member carried by the shaft and having a flat face engaging said spring arm to hold the shaft against negative rotation.

2. A vehicle direction indicator comprising a casing, a shaft journaled in and extending out from the casing, an indicating member fixed to the shaft and extending at right-angles thereto, electromagnets mounted within the casing above and on opposite sides of the shaft, said magnets being of arcuate formation and spaced from one another at their upper ends, an arm, secured to and extending at right-angles from the shaft, an arcuate armature connected to the lower end of the arm and adapted to be attracted by either magnet, said magnets having their opposed faces on their lower ends recessed to receive the arm, an electric circuit for said magnets, means to energize the magnets independently a leaf spring rigidly connected with the casing, and a spring engaging member carried by the shaft and having a flat face for engagement with the leaf spring.

Signed at Riverside, California this 5th day of January, 1916.

WARREN B. MOULTON.
EDWIN W. MOULTON.
